(21) Appl. No.: **29/155,481**

CLAIM

(22) Filed: **Feb. 12, 2002**

The ornamental design for a ventilating system for toilet bowl, as shown and described.

(51) LOC (7) Cl. **23-04**

DESCRIPTION

(52) U.S. Cl. **D23/366**

FIG. 1 is a perspective view of a ventilating system for toilet bowl embodying the design of the present invention.

(58) Field of Search D23/371; 4/213,
4/216, 217

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of environmental structure in FIG. 1 is for illustrative purposes only and forms no part of the claimed design.
